UNITED STATES PATENT OFFICE.

CHESTER H. THORDARSON, OF CHICAGO, ILLINOIS.

POLARIZED RELAY.

No. 876,413.

Specification of Letters Patent.

Patented Jan. 14, 1908.

Application filed March 31, 1904. Serial No. 200,870.

To all whom it may concern:

Be it known that I, CHESTER H. THORDARSON, a citizen of the United States, residing at Chicago, in the county of Cook and State of Illinois, have invented a new and useful Polarized Relay, of which the following is a specification.

This invention relates to polarized relays.

The object of the invention is to provide a polarized relay which is simple in construction and efficient in operation.

A further object of the invention is to provide a polarized relay wherein the work to be performed is accomplished through the attractive force exerted by an electro-magnet upon its armature, the direction of application of the work performed by such armature being controlled by the attractive force exerted upon a polarized armature, that is, wherein the polarized armature merely controls the direction of application of the work and the attractive force of the electro-magnet accomplishing the work required.

Other objects of the invention will appear more fully hereinafter.

The invention consists substantially in the construction, combination, location and relative arrangement of parts, all as will be more fully hereinafter set forth, as shown in the accompanying drawings, and finally pointed out in the appended claims.

Referring to the accompanying drawings, and to the various views and reference signs appearing thereon,—Figure 1 is a view in elevation of a construction of polarized relay embodying the principles of my invention. Fig. 2 is a bottom plan view of the same, showing the polarized armature in centered position. Fig. 3 is a view similar to Fig. 2, showing the polarized armature shifted into position to control the direction of application of the work to be performed by the armature of the electro-magnet. Fig. 4 is a view similar to Figs. 2 and 3, showing the position of the parts upon the operation of the armature of the electro-magnet with the direction controlling armature in position to which it has been actuated, as shown in Fig. 3. Fig. 5 is a view in front elevation, the top plate being removed, of a coin box showing the application thereto of a polarized relay embodying the principles of my invention and illustrating one use to which my invention is applicable. Fig. 6 is a view in side elevation, looking from the righthand side of Fig. 5, with the side plate removed to disclose the

paths taken by the coin when deflected in one direction or the other, according to the operation of the relay.

The same part is designated by the same reference sign wherever it occurs throughout the several views.

In many instances in the useful arts occasion arises for the use of a polarized relay, as, for instance, where it is desired to apply work or power in one direction or the other, such direction being controllable by controlling the direction of the flow of current through a magnet. In apparatus as usually constructed for accomplishing this result a polarized magnet is employed, the polarized armature thereof being actuated in a well known manner in one direction or the other according to the polarity of the magnet in connection with which such armature is used, such polarity being controlled by the direction of flow of current around the magnet. In such instances, however, the polarized armature is shifted or moved merely by the attractive force exerted thereon by the permanent magnetism of the magnet. As is well known, the attractive force exerted by the permanent magnetism of a magnet is weak in comparison with the attractive force exerted by an electro-magnet upon its armature when the circuit of the electro-magnet is closed.

It is among the special purposes of my present invention to provide a construction of polarized relay wherein the work to be accomplished is performed by an electro-magnet, such magnet exerting its attractive force upon the armature thereof, while the polarized armature operating under the influence of the weak permanent magnetism of the magnet is employed merely to control the direction of application of the work performed by the armature of the electro-magnet. In this manner, it will be seen that I am enabled to secure a more efficient and positive action in the accomplishment of the work required by utilizing the greater power of the attractive force of an electro-magnet upon its armature in the accomplishment of the work required than would be possible where merely the attractive force exerted by the permanent magnet upon its polarized armature depended upon for accomplishing the work desired. These desirable objects may be accomplished and carried out in many specifically different constructions and arrangements of appara-

tus. While, therefore, I have shown and will now describe one construction embodying the principles of the invention, I desire it to be understood that my invention is not 5 to be limited or restricted to the exact details of construction and arrangement shown and described.

In the drawings, reference-signs A and B designate magnet spools or coils, having the 10 usual cores C and D.

E designates a permanent steel magnet of the horse-shoe variety arranged in the usual manner with regard to the polarized magnets, that is, having one end thereof arranged 15 to extend over and in coöperative relation with respect to an end of each of the cores C, D, of the electro-magnets, as shown in the upper part of Fig. 5, and carrying an adjustable block F at the other end thereof, in 20 which adjustable block is pivotally mounted a polarized armature G. This polarized armature is arranged to project transversely across the space between the opposite ends of the cores C, D, of the electro-magnets and 25 normally midway between them. Pole pieces H are mounted upon the electro-magnet cores C D at this end, and are provided with enlargements presented towards the polarized armature G, to increase the attractive force exerted by the permanent 30 magnetism upon the polarized armature. The polarized armature G is pivotally mounted in the adjustable block F to swing laterally with respect to itself, that is, back 35 and forth between the pole-pieces H. By this construction and in a manner well known to persons skilled in the art, it will be seen that when current flows through the coils A, B, in one direction the polarized armature will be attracted towards one or the 40 other of the pole-pieces H, according to the direction of flow of the current, and when the direction of the current is reversed the polarized magnet will be rocked or swung in the 45 opposite direction or towards the other pole-piece H; consequently, by varying the direction of flow of current through the coils of spools A and B the polarized armature may be thrown to one side or the other as desired. 50 J designates a stationary part of a soft iron armature for the electro-magnets, upon which stationary part is pivotally mounted the movable part K of the armature having pole-pieces coöperating with the ends or end 55 surfaces of the cores C, D, of the electro-magnets.

If desired, and as shown at L, Fig. 5, the ends or pole surfaces of the cores C, D, of the electro-magnets may be suitably beveled in 60 order to present the most advantageous arrangement. The pole arms of the pivoted soft iron armature portion K are arranged to straddle the extended end of the polarized armature G, that is to say, the extended end 65 of the polarized armature G projects between

the pole arms of the pivotally mounted portion of the armature of the electro-magnet.

Pivotally mounted upon the pivoted armature K is the working member M, that is, the member which is designed to accomplish the work, and which in the specific details of construction thereof depends upon the character of the work to be performed. For instance, and in the example given showing the adaptation, that is where the device is employed in connection with a coin controlling apparatus, that is to control the delivery of a coin into one chute or another, the working member M is provided at each end thereof with pins or projections N, spaced a suitable 70 distance apart to receive and support thereon the coin when properly deposited, as indicated in dotted lines at O, see Fig. 3, it being the object and purpose of the apparatus to deflect or move the coin to the one side or the other according to the circumstances of the case, and in order that the direction of application of this work may be controlled I make use of the polarized armature G as a direction controlling device. To this end I provide 75 means whereby when the polarized armature G is rocked or swung in one direction it will cause the working member M to rock or swing in one direction when the armature K is actuated by completing the circuit of its 80 electro-magnet, and when the polarized armature G is rocked or moved in the opposite direction the working member M will be caused to rock or swing in the opposite direction to that above described when its supporting armature K is actuated. To accomplish this result I provide the movable member M with pins or projections P, Q, on the face thereof and spaced a sufficient distance 85 apart to receive freely therebetween the extended end of the polarized armature G, and in the opposite edges of the extended end of the polarized armature, I provide notches or shoulders R, S, so that when the polarized 90 armature G is rocked or moved in one direction, say to the left from its central position, as shown in Fig. 2, into the position shown in Fig. 3, the shoulder R is brought into position to be engaged by the pin P on the working member M, when armature K is attracted, 95 100 105 thereby causing said working member to be rocked or swung to the right as shown in Fig. 4, and hence causing a movement of the coin in the particular instance given and which is supported by the supporting pins N of the 110 working member, to be moved to the right. If, however, the polarized armature G is moved to the right from its central position as shown in Fig. 2, the shoulder S is brought into position to be engaged by the pin Q of 115 the working member when the armature K is attracted or rocked, thereby causing the working member to be rocked or swung to the left, or in the opposite position from that 120 shown in Fig. 4, and hence delivering or 125 130

moving the coin, in the instance given, towards the left instead of to the right.

From the foregoing description it will be readily seen that the polarized armature is required to perform no work other than to move to the right or to the left, and such movement is accomplished according to the polarity of the permanent magnets in connection with which said armature is associated, and that the work to be accomplished is performed by the attractive force of the electro-magnet exerted upon its armature, the polarized armature merely directing or controlling the direction of application of the work.

T designates a circuit controlling arm arranged to be engaged and moved by a coin, in the instance given, when deposited and resting upon the working member supporting arms N, into position to close circuit connection between the insulated contact strips a, b. These contact strips control the circuit through the coils of electro-magnets A and B, and when the apparatus is in its normal position, as shown in Fig. 2, this circuit is open, but when the coin is deposited, as indicated in dotted lines in Fig. 3, the circuit between the strips a, b, is closed and remains closed so long as the coin in the instance given rests upon the supporting pins N of the working member.

The rocking movement of armature K, under the influence of the attractive force exerted thereon by the energization of the electro-magnet coils, may be yieldingly opposed in any suitable or convenient manner. I have shown a simple arrangement, wherein a spring W is connected at one end to a fixed part or plate A', and at the other end to a projection B' of the pivoted armature K, the tension of said spring being exerted in a direction to retract the armature K. The tension of said spring may be adjusted in any suitable or convenient manner.

In Figs. 5 and 6 I have shown an illustrative embodiment of a coin controlling apparatus, showing one form of use to which my invention may be put. In this exemplification I have shown my invention as applied to the coin box of a telephone apparatus. It is a common system to employ coin boxes in connection with telephones, wherein a person desiring to use the telephone deposits a coin, slug or token into the box as payment for the use of the phone. In case the party using the phone to make a call secures his desired circuit connection the coin, slug or token deposited in the slot is delivered into the coin box, and in case the party making the call does not complete his desired circuit connection the coin, slug or token which he has deposited in the slot is released from the slot and is returned; and the exemplification illustrating one form of apparatus embodying the principles of my invention is a coin

box of this nature, C' designating the inclosing casing, the front plate of which is removed in Fig. 5, and D' the compartment receiving the coin, slug or token, E' the slot into which the coin is delivered. The supporting pins N of the working member of the polarized relay are arranged to project transversely across the raceway of the slot E', as indicated in Fig. 6, and into position to receive and form a support for a coin deposited through the opening E' of the slot. F' designates the raceway for returning the coin, slug or token to the party using the phone in case his circuit connection is not secured, and G' designates a passageway through the inclosing wall of the raceway F' into the coin box or compartment D', and the projecting ends N of the working member of the polarized relay are so relatively arranged with respect to the raceway F' and the passage G' that when with a coin resting on said pins or projections N said working member is rocked or swung in one direction the coin is delivered to the delivery raceway F', and when said working member is rocked or swung in the opposite direction the coin is delivered into the passage G', and thence into the box or compartment D'. While, however, I have shown this apparatus as merely one form of use to which my invention is applicable, I desire it to be understood, and as above indicated, that my invention is capable of general use and is not to be confined to its use in connection with the apparatus shown.

It is believed that the operation of the device will be readily understood from the foregoing description. By merely controlling the direction of current through the coils of electro-magnets the direction of movement of the polarized armature may be controlled. The armature of the electro-magnet moves in a constant direction, that is, it reciprocates back and forth, but the direction of movement of the working member carried by such electro-magnet armature is controlled and directed according to the position of the polarized armature. Therefore, the polarized armature merely operates as a director to control the direction of application of the work to be performed, the actual work being accomplished by the electro-magnet.

Having now set forth the object and nature of my invention and a construction embodying the principles thereof, and having described such construction, its function and mode of operation, what I claim as new and useful and of my own invention, and desire to secure by Letters Patent, is:

1. In a polarized relay, an electro-magnet having pole-pieces, a movable armature for said electro-magnet, a working member carried by said armature, a polarized armature actuated by the attractive force of said pole-pieces, said polarized armature operating

to control the direction of action of said working member.

2. In a polarized relay, a working member arranged to perform work in different directions, an electro-magnet, an armature therefor, connections between said armature and said working member for operating the latter, and means also operated by said magnet for controlling the direction of application of the working member.

3. In a polarized relay, a working member arranged to perform the work required and adapted to operate in different directions, an electro-magnet, a movable armature therefor, and connections between said movable armature and said working member, in combination with a polarized armature arranged to be operated by said magnet, said polarized armature controlling the direction of application of the work of the working member and independently of the direction of operation of said armature.

4. In a polarized relay, an electro-magnet, a movable armature therefor, a pivotally mounted working member connected to said armature, a polarized armature actuated by said magnet, said polarized armature arranged to control the direction of rocking movement of said working member relative to its actuating armature.

5. In a polarized relay, an electro-magnet, a movable armature therefor, a working member pivotally mounted upon said armature, a polarized armature also actuated by said magnet, said polarized armature arranged to control the direction of rocking movement of said working member upon its pivot upon its supporting armature.

6. In a polarized relay, an electro-magnet, a movable armature therefor, a working member pivotally mounted upon said movable armature, a polarized armature, and means whereby the position of the polarized armature controls the direction of rocking movement of said working member when said electro-magnet armature is moved, as and for the purpose set forth.

7. In a polarized relay, an electro-magnet, a movable armature therefor, a working member pivotally mounted upon said armature and provided with engaging pins or projections, a polarized armature extending between said pins or projections and provided with shoulders on opposite sides thereof, said shoulders coöperating with said pins or projections whereby the position of said polarized armature determines the direction of rocking movement of said working member when said electro-magnet armature is attracted, as and for the purpose set forth.

8. In a polarized relay, an electro-magnet, a movable armature therefor, a working member pivotally mounted upon said arma-

ture, pins or projections carried by said working member on opposite sides of the pivot thereof, a polarized armature arranged to extend between said pins or projections and provided with engaging shoulders coöperating with said pins or projections, whereby the position of said polarized armature determines the direction of rocking movement of said working member when said electro-magnet armature is attracted, as and for the purpose set forth.

9. In a polarized relay, an electro-magnet, and a permanent magnet associated therewith, a soft iron armature for said electro-magnet, and a polarized armature for said permanent magnet, a working member actuated by said soft iron armature, and means controllable by the position of said polarized armature for determining the direction of application of the work, as and for the purpose set forth.

10. In a polarized relay, an electro-magnet, and an associated permanent magnet, a soft iron armature for said electro-magnet, and a polarized armature for said permanent magnet, a working member actuated by said soft iron armature to accomplish the work desired, and connections controlled by the position of said polarized armature for controlling the direction of application of the work, as and for the purpose set forth.

11. A polarized relay, comprising in combination an electro-magnet, a movable armature therefor, a working member movably connected to said armature and having two supports, and a polarized armature arranged to control the direction of movement of said working member to withdraw either of said supports as desired.

12. In a polarized relay, an electro-magnet, an armature therefor, a working member pivotally mounted upon said armature and carrying supporting pins or projections, movable contacts, means for closing the circuit between said contacts, and a polarized armature for controlling the direction of rocking movement of said working member upon said armature when the latter is attracted by the energizations of the coils of the electro-magnet, as and for the purpose set forth.

13. In a polarized relay, an electro-magnet, a pivotally mounted armature therefor, means for yieldingly maintaining said armature in retracted position, a working member pivotally mounted upon said armature, and a polarized armature arranged to control the direction of rocking movement of said working member upon its supporting armature when the latter is attracted, as and for the purpose set forth.

14. A polarized relay comprising in combination a permanent magnetic circuit, an electro-magnetic circuit arranged to neutral-

ize a portion of the said permanent magnetic circuit, a polarized armature arranged in the magnetic field of the permanent magnetic circuit, an armature arranged to be influenced by the electro-magnetic field after the permanent magnetic circuit is thus neutralized, a working member operatively connected with the electro-magnetic armature, and means whereby the polarized armature

controls the direction of movement of the 10 working member.

In witness whereof, I have hereunto set my hand this 24th day of March, 1904, in the presence of the subscribing witnesses.

CHESTER H. THORDARSON.
